UNITED STATES PATENT OFFICE.

CHARLES J. MCRAE, OF KANSAS CITY, KANSAS, ASSIGNOR OF ONE-HALF TO
LEMUEL U. COURTER AND JOSEPH C. WELSH, BOTH OF SAME PLACE.

PAPER-FILE.

SPECIFICATION forming part of Letters Patent No. 361,772, dated April 26, 1887.

Application filed February 19, 1887. Serial No. 228,162. (No model.)

To all whom it may concern:

Be it known that I, CHARLES J. MCRAE, of Kansas City, Wyandotte county, Kansas, have invented certain new and useful Improvements 5 in Paper-Files, of which the following is a full, clear, and exact description, reference being had to the accompanying drawings, which form a part hereof.

This invention relates to files for securing 10 bills and papers between a pair of stiff cover-pieces; and it may be said to consist in the devices and the combination and arrangement of devices hereinafter set forth, and pointed out in the claims.

15 In the drawings, which illustrate the manner of carrying out my invention, Figure 1 is a broken longitudinal elevation of the file. Fig. 2 is a broken plan view of the same. Fig. 3 is a detail section showing the arrangement 20 of the clamping devices. Fig. 3^A is a sectional view of the file showing a variation in the form of the clamping devices, the section being taken on line *x* *x*, Fig. 1^A. Fig. 2^A is a broken longitudinal elevation of the file with the varied 25 form of clamping devices applied thereto, and Fig. 1^A is a broken plan view of the same.

The file here shown is designed to be used more especially as a holder for expressmen's bills, or rather as an expressman's delivery-book; but of course it may be used as a permanent file for any desired purpose.

30 A represents a pair of standards, which are provided upon one side, so as to face inwardly, with a series of one or more notches, H, and 35 which are securely fixed at their lower ends to the lower cover-piece, L'. The upper cover-piece, L, is provided with holes, through which the clamping-standards A pass, and it is adapted to rise up and down upon said standards during the operation of the invention.

A pair of rotary cams, B, having a handle, F, formed upon or secured to them, and having a spiral feather, D E, located upon their periphery, are mounted on pivot-pins C, fixed 40 in upper cover, L, as shown.

45 In place of the handle F the cams B can be made in the form of a thumb-screw, if desired, and their operation will be the same, provided they are fitted with the before-mentioned 50 feather.

The spiral feather D E on the cams is made to engage with any one of the notches H in the standards, according to the number and thickness of the sheets of paper that are located between the covers of the file. For instance, if 55 but a few sheets are to be filed, the feather on the cams is made to engage with a notch quite near the lower end of the standards, and likewise, when a considerable number are to be taken care of, the upper cover is raised upward 60 on the standards, as shown by dotted lines, and the feather engages a notch near the upper end of the standards.

For the purpose of providing a more secure foundation for the pivots C and standards A 65 than they would have if they were simply secured in the upper cover, L, I locate a plate of metal, 22, on the upper surface of said cover, as shown.

A circular recess, M, is formed in the periphery of the cams B, or rather in the feathers D E, which is to be engaged by the standards in lifting the upper cover out of its normal position in placing sheets for filing. This recess is located as close to the standards 70 as possible, so that the handle F will come in contact with them when thrown around to loosen up the covers, thereby causing the said recess to register with the standards, whether 75 the operator is particular to make it do so or not, and making the operation more certain 80 than it would be were said recess otherwise located.

The operation of this construction is as follows: The sheets to be filed are first perforated in any desired way, so as to engage the standards A. Then cams B are loosened by being revolved until the recess therein registers with the body of the respective standards, after which the upper cover, L, is removed, the 90 sheets to be filed are placed upon the standards, the removed cover is replaced, and the cams B are revolved in an opposite direction until a sufficient pressure is placed upon the sheets to securely hold them in place. The 95 operation of removing sheets from the file will be just the reverse of this, and may be easily done.

In the varied form of clamping devices shown in Figs 3^A, 2^A, and 1^A the standards A are pro- 100

vided with a series of projections or shoulders, H, upon opposite sides—that is, the said projections are located on the standards in opposite pairs, and a laterally-sliding cam-plate, 8, 5 having an inclined plane, 11, is to be used in lieu of the cams shown and described in the first part of the specification. The inclined planes 11 are located upon the upper side of the plate 8. Said plate is provided with a longitudinal slot, 23, near each of its ends, which is engaged by the standards, and by means of which the plate is held in position upon the upper cover of the file. It is also provided with a centrally-located slot, 9, which is engaged by 15 a thumb-screw, 10. This screw passes through the plate into the body of the upper cover, and may be tightened up or loosened, as the case may be, for the purpose of holding the cam-plate in whatever position it may be placed.

20 The operation of this latter construction is as follows: When the sheets are to be removed from the file, cam-plate 8 is pushed toward the right hand in Fig. 3^A, the thumb-screw 10 being of course loosened up first, until the circular 25 recess 24 at the left-hand end of the slots 23 registers with the body of the standards, which operation, as will be seen, will permit the upper cover to be removed, and so on.

Having thus described my invention, what 30 I claim is—

1. A paper-file constructed with clamping-standards having notches upon their body and provided with cams which engage the notches, substantially as set forth.

2. A paper-file comprising an upper and a 35 lower cover, standards upon which the paper is impaled, said standards provided with notches, as described, and cams which engage the notches in the standards to press the two covers together, substantially as set forth. 40

3. In a file of the class described, the combination, with the lower cover, of the standards A, having notches, as described, and securely fixed to the lower cover, the upper cover provided with holes, through which said 45 standards pass, and cams which engage the notches in said standards to urge the covers toward each other, substantially as set forth.

4. In a paper - file, a cam having a handle located at a suitable point upon its body and 50 provided with a spiral feather, substantially as set forth.

5. In a paper - file, the combination, with lower cover, L', of a standard, such as A, having notches, as described, upper cover, L, a 55 cam, B, having feather D E on its periphery, pivot-pin C in the upper cover, and upon which said cam is mounted, and a suitable handle for the cam, substantially as set forth.

In testimony whereof I affix my signature in 60 presence of two witnesses.

CHARLES J. McRAE.
